UNITED STATES PATENT OFFICE.

GEORGE A. MOON, OF SAN FRANCISCO, CALIFORNIA.

SHOE-FASTENING.

1,358,647.

Specification of Letters Patent. Patented Nov. 9, 1920.

Application filed October 7, 1919. Serial No. 329,099.

To all whom it may concern:

Be it known that I, GEORGE A. MOON, a citizen of the United States, residing at the city and county of San Francisco and State 5 of California, have invented new and useful Improvements in Shoe-Fastenings, of which the following is a specification.

This invention relates to fastening means, and particularly pertains to a shoe fastener 10 for laced shoes.

Due to the fact that considerable time is lost and there is quite a bit of inconvenience in lacing and unlacing shoes, it is thought of advantage to provide some improvement in 15 laced shoe fasteners; and it is the principal object of the present invention to provide a fastening means which embodies the use of a shoe lace, and which will insure that the shoe may be instantly fastened or unfastened 20 without removing the laces from their original position through the eyelets of the shoe-upper.

The present invention contemplates the use of a false upper piece, through which 25 eyelets are formed and which is detachably secured to the main upper by means of fasteners which may be instantly brought into engagement or caused to disengage, thus permitting the shoe to be readily fastened or 30 unfastened, as the case may be.

The invention is illustrated by way of example in the accompanying drawings, in which—

Figure 1 is a view in side elevation, showing 35 a shoe equipped with the present invention.

Fig. 2 is an enlarged view in perspective, illustrating the upper of a shoe and more clearly disclosing the present invention and 40 the manner in which it acts to fasten the halves of the shoe upper together.

Fig. 3 is an enlarged view in central section through the fastening member, showing 45 the hook engagement of the two fastening elements.

Referring particularly to the present drawings, it will be seen that an ordinary shoe is illustrated as having the usual laced upper. This upper portion is adapted to be 50 opened and its contiguous edges are provided with eyelets 10, which are arranged along the opposite flaps 11 and 12 of the upper. Threaded through these eyelets is a shoe lace 13, which lace is also threaded 55 through eyelets 14 of a fastening pad 15. This pad is preferably made of leather and

is designed to match the leather of the shoe and to conform to the style and contour thereof.

By reference to Fig. 2 of the drawings, it 60 will be seen that the eyelets are continued in their arrangement along the edge of the flap portion 11 and that they are only arranged for a portion of the length of the flap 12. The eyelets which are omitted from the flap 65 12 are supplemented by the eyelets 14 of the fastening pad 15. Thus it will be seen that, when the pad is in proper position and secured in a manner which will be hereinafter set forth, a continuous row of eyelets will be 70 provided along each of the flaps 11 and 12 and it will be possible to properly lace the shoe and tie the end of the lace in the manner now common.

The pad member 15 not only carries a 75 plurality of eyelets 14 but also a series of metallic hook members 16. These are complementary to fastening hooks 17 formed along the flap 12 and in place of the usual eyelets 10, which would be arranged throughout the length of this flap. The hooks 16 and 17 are so arranged in relation to each other as to either be brought into engagement by hooking completely over each other or by slipping sidewise and between the 80 jaws of the hook portions, and are formed in such a manner as to become interlocked so that accidental movement will not disengage them. This may be accomplished in the present instance by forming the hooks with 85 a concaved transverse section.

In the operation of the present invention the pad 15 is placed in proper position upon the flap 12 and thereafter the lace 13 is woven through the eyelets 10 and 14, in any 95 desired fashion, to fasten the shoe. When it is desired to unfasten the shoe, the knot of the lace need not be molested, and it will only be necessary to pull upwardly upon the pad member 15, which will cause the hooks 100 16 to move laterally from their seating position within the hooks 17 and permit the pad 15 to become disengaged from the flap 12. When the pad has been removed it will appear as shown in Fig. 2 of the drawings and 105 will thus permit the shoe to be easily removed from the foot.

It will thus be seen that the invention here disclosed, while quite simple as to its structural elements, at the same time provides convenient and inexpensive means for fastening a laced shoe and insuring that it 110

may be easily removed from the foot of the wearer or fastened thereupon in a minimum amount of time.

While I have shown the preferred form of my invention as now known to me, it will be understood that various changes in the combination, construction and arrangement of parts may be made by those skilled in the art without departing from the spirit of the present invention as claimed.

Having thus described my invention, what I claim and desire to secure by Letters Patent is—

1. A laced shoe in which the vamp is separated into two parts, opposing eyelets in the edges of the lower parts of the opening, a single lacing string crossing from side to side through said eyelets, an independent flap disposed interior to the upper parts of the separated sides of the vamp opening, eyelets in one edge of said flap and corresponding eyelets in the adjacent edge of the vamp opening, eyelets in one edge of said flap and corresponding eyelets in the adjacent edge of the vamp opening, through which the lace member is passed, hooks fixed to the opposite edge of the flap having their line of pull transverse to the vamp opening, and co-acting hooks fixed to the opposite edge of the vamp opening, said

hooks having their open sides transverse to the line of pull, and the openings of the first named hooks, to enable the hooks to engage or disengage in line transverse to the pull when the vamp opening is to be separated.

2. In combination with a laced shoe having separable upper flaps along which eyelets are arranged and through which a shoe lace may be threaded, a pad member formed with a plurality of eyelets to complete the row of eyelets along one side of the shoe flap, a plurality of hook-shaped fasteners secured to the flap in lieu of the missing eyelets, said fastener being convex in transverse section, and a plurality of complementary fastening members carried by the pad and of convex section and adapted to be shifted transverse to the line of pull when closed to interlock with the fastening members of the flap and to thereby complete the lacing of the shoe.

In testimony whereof I have hereunto set my hand in the presence of two subscribing witnesses.

GEORGE A. MOON.
